FUSIBLE EXTENSION CORD PLUG

Arthur G. Bauer, Wantagh, N. Y., assignor, by
mesne assignments, to Charles E. Eggers, Great
Neck, N. Y.

Original application November 8, 1946, Serial No.
708,547. Divided and this application October
5, 1949, Serial No. 119,735

1 Claim. (Cl. 339—195)

1

This invention relates to improvements in a quick detachable connecting plug for electric extension cords and the like. The invention is more particularly concerned with an attachment plug of novel construction and which is adapted for use with a fuse element whereby both legs of the extension cord circuit are protected against overload as well as short circuiting. The plug may be used with greater safety in connecting usual electric appliances, such as lamps, flat irons, toasters, and the like to the terminals of outlet sockets and was first shown and described in my co-pending application, Serial No. 708,547, filed November 8, 1946, which has matured into Patent No. 2,486,380, and of which this application is division.

An object of the invention is, therefore, the provision of an improved electrical connection plug having a recessed outer end into which may be fitted a readily accessible and exchangeable fuse element which substantially fills the recess and covers the wire terminals therein, whereby in the event of an overload or short circuit in the plug circuit the fuse is caused to burn and interrupt the circuit, thereby preventing damage to the plug or appliances connected thereto.

Another object of the invention is the provision of an improved plug member in which the circuit may be interrupted at the plug to thereby render appliances safe for handling at any time desired, which are connected in the circuit with the plug.

A further object of the invention is the provision of an electric plug for use with a circuit controlling fuse mountable in the outer end thereof so that the fuse may be readily examined for removal or replacement only upon withdrawal of the plug from an associated line socket and thereby breaking the circuit through the plug without danger of burns or shock in so doing.

A still further object of the invention is the provision of a one-piece plug having pairs of terminal contacts and cord binding connections disposed within a recessed chamber in the outer or prong end of the plug adapted for use with an insulated fuse containing member for bridging the contacts and being removably supported within the recessed chamber so as to provide a closure for the chamber and a protecting cover for the contacts and binding cord connections therein.

A still further object of the invention is the provision of an improved electrical plug com-

2

prising a body which is preferably constructed in one piece from any suitable insulating material, such as rubber, the body having a relatively deep recess in one end thereof with opposed walls of the recess provided with transversely aligned slots opening through the ends of the walls, the plug also having a pair of spaced contacts at each of two opposite sides of the recess with one contact of each pair being integral with a socket engaging prong projecting outwardly from the recess, and the recess being adapted to receive a circuit completing member having end portions removably receivable in the slots for facilitating removal of the member by engagement of the end portions by the fingers.

Other objects and advantages of the invention will become apparent in the course of the following description, taken in connection with the accompanying drawings, wherein:

20 Fig. 1 is an end view of the improved plug as observed from the left of Fig. 2, the view being on a substantially enlarged scale;

Fig. 2 is a vertical sectional view as observed in the plane of line 2—2, Fig. 1;

25 Fig. 3 is an end view of the plug corresponding to Fig. 1, but showing a fuse member in operative position within the recessed end thereof;

Fig. 4 is an elevational view of the plug as viewed from one side thereof; and

30 Fig. 5 is an elevational view of the plug as viewed from another side thereof and being partly in section to show a fuse member in operative association with a terminal contact within the recess in the plug.

35 All of the views of the drawings as briefly described above show the structure of the plug about double actual size.

Referring now in detail to the drawings, P designates the improved electric cord plug, which, as shown, embodies a one-piece insulating body member 10 provided with a relatively deep and substantially rectangular recess 11, in one end thereof. The body is shown as further provided with a cord receiving aperture 12, opening through the opposite end thereof and which aperture opens into the recess 11, through an elongated recess portion 13. The body is further provided with slots 14 in opposed walls thereof opening into recess 11. While the body 10 may be constructed of any suitable insulation material, it is preferably constructed of rubber which is readily molded to desired shape and unbreakable in the event of impact with hard objects.

This body 10 is also provided with a pair of socket engageable prongs 14 each of which is constructed from a strip of spring brass which is folded over in the provision of yieldable terminal portions 15, for frictional fit within the socket member. The strip is further bent over in the provision of attaching portions 16, embedded in the body 10. The prongs 14 each further includes a contact 17, disposed laterally of the prong proper, as is clearly indicated in Fig. 1. The contacts 17 are preferably provided as offset continuations of the strips from which the prongs are formed.

As is indicated in Fig. 1, each contact 17 is disposed to one side of its respective prong in diagonally opposed corners of the recess 11. A contact 18 is disposed in each of the other diagonally opposed corners of the recess 11 adjacent but spaced from a prong 14 and these terminal contacts include base portions 19, which are provided with tapped apertures 20, formed by extruding the metal from the base portions. The tapped apertures are adapted to receive the cord binding screws 21 whose shanks may extend into the recesses 22, in the body 10. The terminal contacts 18 further include doubled-over foot portions 23, anchored in the body.

As is more clearly indicated in Fig. 2, the prong contacts 17 and terminal contacts 18, which are also preferably of spring brass, include similar rounded grooves 24 and 25 respectively for a purpose later to appear. Also as indicated in Fig. 1, the contacts 17 and 18 are disposed in pairs adjacent the prongs 14 with the contacts of each pair disposed in alignment at opposite sides of the respective prong.

In the use of the plug P an electric cord is removably entered into or molded in the plug through apertures 12-13 and the two wires of the cord may be individually clamped to the base portions 19 of the terminal contacts 18, by means of the screws 21. Instead of using the screw type binding post 21 it will be understood that any well known or approved terminal connections may be substituted, or the cord wires may be soldered directly to the terminal members 18, without altering the invention.

The construction of the plug, as described and shown in Fig. 1, is such that current cannot be conducted from the prongs 14 to the cord wires through the terminal contacts 18, unless the contacts 17 and 18 adjacent each prong are placed in an electrical circuit. As shown this may be effected by a fuse member F, illustrated in operative association with the plug in Figs. 3, 4 and 5. This fuse member may embody a pair of superimposed mating shells 26 connected by side terminals 41 and having reduced end portions 26a, which may be formed of suitable relatively rigid transparent insulating material.

It is to be particularly noted that the fuse member F is insertable within and removable from the recess 11 by movement thereof axially of the plug, since the prongs 14 ride in the recesses 45 in the shells 26, and by reason of such mounting a fuse cannot be inspected or replaced until the plug is withdrawn from a wall or other line socket thereby avoiding any possible danger of burn and shock in examining or replacing the fuse member.

It is to be further noted that with the improved form of plug the fuse member when in position within the recessed end of the plug (see Fig. 3) provides an adequate cover for the binding screws 21 and associated cord ends. Since the reduced shell end portions 26a of the fuse seat in the slots 11a, in the assembled position of the fuse and plug members and project slightly beyond the adjacent wall portions (see Fig. 4), these ends of the fuse may be grasped by the fingers and the terminals 41 of the fuse member F easily withdrawn from their normal operative association with the contacts 17 and 18. With the fuse removed the plug and appliance cord connecting the binding screws therein is rendered inoperative even if reinserted into the wall socket. Hence, the reinserted plug element, as shown in Figs. 1 and 2 without the fuse therein, provides a further safety means against tampering by children etc.

While I have herein disclosed my invention in a preferred form, it is obvious that changes in structure may be resorted to without departing from the spirit of the invention, and I therefore do not desire to be limited to the precise form disclosed beyond the limitations imposed by the following claim.

What I claim and desire to secure by U. S. Letters Patent is:

An attachment plug comprising a one-piece body member having a substantially rectangular and relatively deep recess in one end thereof for the removable reception of a circuit completing generally rectangular closure member having laterally projecting finger engageable extensions, a cord receiving aperture extending through the opposite end of the body member and communicating with said recess centrally thereof, a pair of terminal contacts supported by the body member at the base of said recess at opposite sides of said aperture and each provided with a binding screw, a pair of socket engageable prongs supported by the body member and each provided with a contact in spaced and laterally aligned relation to one of said terminal contacts, one of each of said first contacts and second contacts being disposed adjacent one wall of the recess at opposite sides of one prong, the other of said first and second contacts being disposed adjacent the opposite wall of the recess at opposite sides of the other prong, and said body member being provided with a relatively deep slot in each of the other opposite walls of the recess and opening through the upper edges thereof for receiving said finger engageable extensions.

ARTHUR G. BAUER.
